CLAIM

The ornamental design for a water bottle as shown and described.

DESCRIPTION

FIG. 1 is a perspective view of a water bottle according to a first embodiment showing our new design;

FIG. 2 is another perspective view shown in an unfolded state thereof;

FIG. 3 is a front elevational view of the water bottle shown in FIG. 1;

FIG. 4 is a rear elevational view thereof;

FIG. 5 is a right elevational view thereof;

FIG. 6 is a left elevational view thereof;

FIG. 7 is a top plan view thereof;

FIG. 8 is a bottom plan view thereof;

FIG. 9 is a perspective view of a water bottle according to a second embodiment showing our new design;

FIG. 10 is another perspective view shown in an unfolded state thereof;

FIG. 11 is a front elevational view of the water bottle shown in FIG. 9;

FIG. 12 is a rear elevational view thereof;

FIG. 13 is a right elevational view thereof;

FIG. 14 is a left elevational view thereof;

(Continued)

FIG. 15 is a top plan view thereof; and,
FIG. 16 is a bottom plan view thereof.
